GAS RANGE COOKING TOP

Claude E. Parker, Chicago, Ill., assignor to Gas Products Corporation, Chicago, Ill., a corporation of Illinois

Application February 29, 1940, Serial No. 321,499

2 Claims. (Cl. 126—39)

The invention relates to a gas range cooking top. The present application is a continuation in part of my copending application Serial No. 272,984, filed May 11, 1939, now Patent No. 2,257,396, September 30, 1941.

Generally stated, the object of the present invention is to provide in a gas cook stove, a novel arrangement of parts to facilitate the adjustment of the primary air and fuel mixture for the burner or burners.

More specifically, it is an object of the invention to provide in a cook stove having a continuous top plate or panel, apertured only for the burner units, an improved arrangement of the parts such that the shutters for the primary air to the burners and the needle valve controlling the supply of raw gas can be adjusted by reaching down through the burner unit holes in the top plate and without the necessity of removing the top plate or the burners themselves.

Another object is to provide in a cooking top structure having a top burner and front wall an improved construction and arrangement permitting the easy insertion and removal of the burner heads.

Further objects and advantages of the invention will become apparent as the following description proceeds taken in connection with the accompanying drawing in which:

Figure 1 is a fragmentary plan view of a cooking top, embodying the present invention, a portion of the structure being broken away to show the location of the primary air adjustment shutters.

Fig. 2 is a fragmentary plan view of one of the burner units with the grate removed.

Fig. 3 is an enlarged front elevation of one of the primary air adjustment mechanisms.

Fig. 4 is an enlarged side elevation of one of the burner units, with the top plate in section substantially along the line 4—4 in Fig. 1.

While the invention is susceptible of various modifications and alternative constructions, I have shown in the drawing and will herein describe in detail, the preferred embodiment, but it is to be understood that I do not thereby intend to limit the invention to the specific form disclosed, but intend to cover all modifications and alternative constructions falling within the spirit and scope of the invention as expressed in the appended claims.

For purposes of exemplification, the invention has been shown and described herein as embodied in a cook stove of the modern cabinet or closed top type in which the front wall is

closed, with only the burner control handles 10 projecting through it (Fig. 1). On the top of the stove is a porcelain enameled sheet metal top plate 11, substantially imperforate and completely closing the top of the stove except for a series of round burner apertures 12.

Though various forms of burner heads may be used, a radial arm type, and particularly the three arm form shown, is especially desirable in 10 a stove embodying the present invention, for reasons which will appear below. As indicated, the burner units embody heads 13 and 14, which are of the Bunsen type and are ported to emit flames upwardly and laterally beneath utensils 15 (not shown) seated above the same. Other than for the feature noted, the construction of the heads is not concerned in the present invention and hence need not be detailed here. These burner heads are suitably mounted beneath the apertures 12 as, for example, on horizontal rods 12a (Fig. 4). Both of the burners are supplied with gas from a manifold 15 extending along the front of the stove beneath the top plate 11. In the case of the front burner head 14, the gas 20 is led from the manifold 15 through a control valve 16, manually operated by the corresponding handle 10, and a Venturi tube 17. Similarly, gas is supplied to the rear burner head 13 from the manifold 15 through a control valve 18 and 25 a Venturi tube 19. The Venturi tubes 17 and 19 are disengageably supported in the conventional manner upon the nozzles of the control valves 16.

At the inlet end of the front burner Venturi tube 17 is a primary air control means, shown 30 (Fig. 3) in the form of a pair of sheet metal shutters 20 pivoted on the front end of the tube by a screw 21 and overlying primary air inlet ports 22. By swinging these shutters about their pivot 21, the amount of air entering the ports 22, and mixed with the gaseous fuel, can, of course, be regulated as desired. Integral ears 23 at the upper corners of the shutters, located in positions to be easily grasped, facilitate their adjustment. An identical primary air adjustment means is provided on the Venturi tube 19 for the rear burner head.

To regulate the flow of raw gas into the front burner Venturi tube 17, a needle valve 24 (Fig. 4) 40 of conventional form is provided. It is adjustable by rotation of a hexagonal collar 25. A similar needle valve 26 (Fig. 1) is provided for the rear burner.

In accordance with one aspect of the present 45 invention, the primary air regulating shutters 20

and the needle valves 24 and 26 for both the front and rear burners 14 and 13 are located in registry with, and beneath, the top plate aperture 12, which receives the front burner unit. It will be observed, upon reference to Fig. 2, that the three-arm front burner head 14 is arranged with one of its arms projecting forwardly and the Venturi tubes 17 and 18 are disposed on opposite sides of this arm and in the spaces between such arm and the respective adjacent rear arms of the burner head. Consequently, ample clearance is provided, in so far as the burner head itself is concerned, for easy access to the adjustable shutters 20 on the respective Venturi tubes even though the latter are located within the confines of a circle circumscribing the burner head. Equally easy access to the needle valves is also afforded. The aperture 12 is large enough so that the shutters and needle valve adjustment collars lie within its confines and are completely exposed for easy manipulation simply by removing one part, namely, the grate 27. Also to be particularly noted is the fact that the shutters 20 and the needle valves are located closely adjacent the top plate 11 (Fig. 4) so that they can readily be reached through the top plate aperture 12, and their position of adjustment easily observed.

Removably mounted in the top plate apertures 12, above the burner heads 13 and 14, are utensil supporting grates 27 of any suitable form. They may if desired be in the form of removable hearth and utensil support units like that shown in my copending application Serial No. 272,984 referred to above and in which event the refractory material of the hearth overlies and thermally protects the needle valves. In the present instance the utensil supports embody simply a cast iron border ring with integral, inwardly projecting utensil supporting fingers on it.

To adjust the regulating shutters 20 for either the front or rear burners 14 and 13, it is necessary simply to remove the grate 27 for the front burner head. Thereupon the shutters 20, for both of the Venturi tubes 17 and 18, are exposed (as in Fig. 2) for ready access through the front burner opening 12 in the top plate 11. To effect the necessary adjustments the operator grasps the ears 23 and shifts the position of the shutters 20 until the primary air and fuel mixture is such as to give a desired condition of combustion. Similarly, to adjust the needle valves 24, 26, the operator simply reaches down in the same hole and adjusts the valves as required with the usual orifice wrench.

To those familiar with the procedure previously followed in making primary air and needle valve adjustments, the simplicity of manipulation for the present apparatus will be remarked at once. All of the usual cumbersome business of disassembling practically the entire top of the stove, in order to gain access to the adjusting means, is obviated. In other words it is no longer necessary to remove a plurality of grates, key plates, front panels and various other parts to get at the shutters which have heretofore been buried

deep beneath the stove top structure. Consequently, it is possible, by virtue of the present invention, to utilize a substantially closed or cabinet top on the stove and particularly, a continuous 5 top plate apertured only for the burner units, and still obviate any difficulties of adjustment for the burners.

It will also be observed that the construction and arrangement set forth permits of the easy 10 insertion and removal of the burners from the stove. For this purpose it is only necessary to remove the grates 27 and lift the burner heads out of their respective apertures in the top as permitted by the disengagable connection between 15 the Venturi tubes 17 and 18 and the nozzles of the gas valves 16, it being noted that the apertures in the top panel are relatively large as compared to the size of the burner heads.

I claim as my invention:

- 20 1. In a gas cook stove, the combination of a sheet metal top plate having front and rear burner apertures therein and otherwise substantially imperforate so as to present a closed top, burner heads substantially triangular in form in 25 respective ones of said apertures, each of said burner heads presenting a plurality of radially projecting arms, the front burner having one arm projecting forwardly toward the front of the stove, a Venturi supply tube for each of said heads 30 having an adjustable air regulating shutter at its inlet end, means to supply gas to said Venturi tubes, and utensil supporting grids removably seated upon said top plate and overlying the burner heads, said shutters for both of said Venturi tubes being located directly beneath and accessible through the top plate aperture for the front burner and disposed on opposite sides of the forwardly projecting arm on the front burner and substantially equidistantly therefrom.
- 35 40 2. A gas cook stove having, in combination, a sheet metal top plate, a gas supply manifold along and beneath the forward edge of the top plate, said top plate having front and rear burner apertures with a common center line extending perpendicular to said manifold and being otherwise substantially imperforate so as to present a closed top, a burner head supported centrally in each of said apertures and each having rigid therewith a mixing tube extending forwardly therefrom for 45 disengagable association with said manifold, and utensil supporting grids removably mounted on said top plate above said burner heads, the tubes for the front and rear burners being disposed in closely spaced parallel relation on opposite sides 50 of said common center line with the forward ends of the tubes terminating closely beneath the forward edge of the front burner aperture, said mixing tubes having individual regulating means thereon, accessible through such front burner 55 aperture upon the removal of the front utensil supporting grid only, said burner apertures being sufficiently large relative to the size of the burner heads to permit removal of said heads and their mixing tubes through said apertures.
- 60 65 60 CLAUDE E. PARKER.
